UNITED STATES PATENT OFFICE.

WILLIAM W. GARDINER, OF NEW YORK, N. Y.

IMPROVEMENT IN KNOB-LATCHES.

Specification forming part of Letters Patent No. 173,853, dated February 22, 1876; application filed January 15, 1876.

To all whom it may concern:

Be it known that I, WILLIAM WALLACE GARDINER, in the city, county, and State of New York, have invented a new and useful Improvement in Knob-Locks, of which the following is a specification:

Figure 1 is a vertical section of a door to which my improved lock has been applied, the side plate of the lock being removed; Fig. 2 is a vertical section of the same taken through the line *xx*, Fig. 1; Fig. 3 is a detail section taken through the line *yy*, Fig. 2, looking in the direction of the arrow; Fig. 4 is a detail view of the key-hole escutcheon.

Similar letters of reference indicate corresponding parts.

The object of this invention is to furnish an improved lock, which shall be so constructed that the key may be inserted through the knob and spindle that operate the catch-bolt, and which shall be simple in construction, neat in appearance, reliable in use, and will avoid cutting key-holes in the doors.

The invention consists in the combination of the lugs, the ring-plates, and the end plate with the spindle, the lock-case, and the knob, and in the combination of the lever notched to receive the lugs of the knob and of the spindle, and the pin with the knob, the knob-spindle, and the lever and block that operate the catch-bolt, as hereinafter fully described.

A represents the lock-case; B represents the lock-bolt; and C the catch-bolt. D is the lever by which the catch-bolt C is operated.

E is the block by which the lever D is usually operated, and which in ordinary locks is attached to and operated by the knob-spindle, but which in this case works upon a pivot attached to the case A, and is made with a toe, *e*¹.

F is the knob, which may be made of wood, metal, or other suitable material, and which works upon the spindle G, upon which it is secured by a plate, H, placed in the concaved head of the knob F, and secured by screws to the end of the spindle G.

To the face of the plate H is hinged a cap plate, *h'*, to cover the key-hole *g*¹, which passes through the plate H, and longitudinally through the spindle G. The inner end of the knob-spindle G has lugs *g*² formed upon its opposite sides to receive the screws or bolts I, by which it is secured to the lock-case A. The inner ends of both spindles G may be secured by the same bolts I, if desired.

The spindles G are stiffened and strengthened by the ring-plates J, which surround the spindles G and the shank of the knob F, rest against the opposite sides of the door and have projections upon their inner sides to rest upon the lugs *g*¹, and have holes formed through them to receive the screws or bolts I, so that the knob-spindles may be bolted to the lock-case and at the same time clamped to the door.

K are lugs formed upon the end of the shank of the knob F, or upon a ring attached to said end, according to the material of which said knob is made.

The lugs K enter notches *e*¹ in the outer side of the lever L, which hangs and works upon the spindle G, so that the said lever can be worked by turning the knob F. In the inner side of the lever L are formed wide notches *e*², to receive the necks of the lugs *g*², so that the knob F and lever L can be worked upon the spindle G.

The lower ends of the two levers L are attached to the opposite ends of a pin, M, that passes through a curved slot in the lock-case A, and between the lever D and the toe *e*¹ of the block E, so that when the knob F is turned to move the pin M in one direction it pushes against the lever D and draws back the catch-bolt C, and when turned in the other direction the pin M pushes against the toe *e*¹ of the block E, and the said block operates upon the lever D to draw back the catch-bolt C, so that the said catch-bolt may be drawn back by turning either knob F in either direction.

Having thus described my invention, I claim as new and desire to secure by Letters Patent—

1. The combination of the lugs *g*², the

ring plates J, and the plate H, with the spindle G, the lock-case A, and the knob F, substantially as herein shown and described.

2. The combination of the lever L, notched to receive the lugs K and g^2 , and the pin M, with the knob F, the knob-spindle G,

and the lever and block D E, that operate the catch-bolt C, substantially as herein shown and described.

WILLIAM W. GARDINER.
